UNITED STATES PATENT OFFICE.

FREDERICK HAUFF, OF AKRON, OHIO, ASSIGNOR TO THE GENERAL NOVELTY COMPANY, OF AKRON, OHIO, A CORPORATION OF OHIO.

DESIGN FOR AN INFLATABLE TOY.

Application filed January 21, 1929. Serial No. 29,697. Term of patent $3\frac{1}{2}$ years.

To all whom it may concern:

Be it known that I, FREDERICK HAUFF, a citizen of the United States, residing in Akron, in the county of Summit and State of Ohio, have invented a new, original, and ornamental Design for Inflatable Toys, of which the following is a specification, reference being had to the accompanying drawings forming a part thereof.

I claim:

The ornamental design for an inflatable toy as shown.

FREDERICK HAUFF.
